(57) **CLAIM**

I claim the ornamental design for an intervertebral spinal stabilization device, as shown and described.

DESCRIPTION

FIG. 1 is a front perspective view of the intervertebral spinal stabilization device;

FIG. 2 is a back perspective view of the intervertebral spinal stabilization device;

FIG. 3 is a top view of the intervertebral spinal stabilization device;

FIG. 4 is a front view of the intervertebral spinal stabilization device;

FIG. 5 is a right view of the intervertebral spinal stabilization device;

FIG. 6 is a back view of the intervertebral spinal stabilization device;

FIG. 7 is a left view of the intervertebral spinal stabilization device; and,

FIG. 8 is a bottom view of the intervertebral spinal stabilization device.
